UNITED STATES PATENT OFFICE.

CLAYTON HOBERT, OF PHILADELPHIA, PENNSYLVANIA.

BEDSPRING SUPPORT.

Application filed March 1, 1922, Serial No. 540,090. Renewed September 22, 1923.

To all whom it may concern:

Be it known that I, CLAYTON HOBERT, a citizen of the United States, residing at Philadelphia, in the county of Philadelphia and State of Pennsylvania, have invented certain new and useful Improvements in Bedspring Supports, of which the following is a specification.

My invention relates to bed springs, and particularly to auxiliary spring mechanism adapted to advantageously reinforce the yielding bed bottom as hereinafter fully set forth and clearly defined in the claims.

Among the objects of the invention is to provide improved resilient supporting means for the intermediate portion of the bed spring.

A further object is to provide a supporting means which will have an equalizing action when one side of the bed bottom fabric is depressed, and a still further object is to provide a supporting means of the nature described which may be adjusted to take up any sag in the bed bottom fabric and, if desired, to even raise the intermediate portion of the bed bottom fabric above the normal plane.

With the foregoing and other objects in view as will be hereinafter more specifically brought out, reference will be had to the accompanying drawing forming a part of this specification and wherein like characters of reference designate corresponding parts throughout the several views, in which:

Fig. 1 is a longitudinal vertical sectional view of a bedstead with the invention applied thereto,

Fig. 2 is a transverse vertical sectional view taken on the line 2—2 of Fig. 1,

Fig. 3 is a top plan view of the transverse bed bottom fabric supporting bar showing fragments of the bed bottom fabric, and

Fig. 4 is a fragmentary horizontal sectional view taken through Fig. 2 on the line 4—4 thereof.

Referring to the accompanying drawing, reference numeral 1 designates the head, 2 the foot, and 3 the side rails of a bedstead. The bed bottom fabric 4 is mounted in any well known or desired manner as upon a supporting frame 5 with usual risers 6. This bed bottom fabric while illustrated as being of woven fabric, may be of any of the well known constructions, such as wire coils, links or the like, and in fact, the bottom

fabric forms no part of this invention, but to the contrary the invention is intended as an attachment for all forms of bed bottom fabrics.

At any desired point between the ends of the bottom fabric is arranged a transverse supporting bar 7, the same being attached to the bottom fabric by means of straps 8 passed through end slots 9 in the transverse bar and secured by buckles 10. While two straps 8 are illustrated in Figs. 2 and 3, one at each end of the bar 7, it will be understood that in some cases it will be desirable to employ other such straps in the intermediate slots 9 of the bar 7, or it may be preferable to employ a single strap to extend entirely across the bar 7 looping in an obvious manner through all of the slots 9 and engaging with certain of the strands of the bottom fabric.

Depending centrally from the transverse bar 7 is a post 12, preferably braced by members 14 extending from the post to portions of the bar 7, and this post is circular in cross-section and has its lower end threaded as indicated by reference numeral 15 to receive a nut 16. This nut is provided with a circular flange 17 equipped at intervals with apertures 18 regularly spaced apart and with certain of which the inner ends of pairs of coil tension springs 19 and 20 connect. The outer ends of the springs of the pair 19 connect with apertures 21 in the ends of plates 22, and similarly the outer ends of the springs of the pair 20 are attached to a like plate 22. Each of these plates 22 is provided at each end with an aperture 24 through each of which passes a strap 25, and these straps are passed around the side rails of the bedstead and secured by buckles 26.

The bar 7 with its post 12, braces 14 and nut 16, as well as the plates 22 may be constructed of aluminum for lightness, though other metals will serve where lightness is not a factor, and the straps 8 and 25 may be of leather, fabric or metal.

In use, when a person sits on the edge of the bottom fabric, one end of the transverse bar will be depressed, thereby throwing the lower end of the post over toward the opposite side of the bedstead, stretching the pair of springs on the depressed side, the amount of depression and lateral movement of the bed bottom and the post being regulated by the adjustment of the nut 16 on

the post 12. When a person is lying in the bed the full benefit of the springs on both sides will be had to prevent undue sagging or uneven depression of the bottom fabric. 5 Thus it will be seen that there is not only an equalizing action, but should the bottom fabric become permanently stretched this objection may be overcome or neutralized by simply adjusting the nut 16 to increase the resistance of the springs 19 and 20.

What I claim is:

1. In a device of the character described, the combination with a side-bar bedstead and a bed bottom, of a bed bottom supporting device comprising a transverse element having a single depending portion, a nut threaded thereon, and springs connecting said nut and the side bars of the bedstead.
2. In a device of the character described, the combination with a side-bar bedstead and a bed bottom, of a bed bottom supporting device comprising a transverse element having a single depending portion, a flanged nut threaded on the lower end thereof, and tension springs connecting said nut flange and side bars of the bedstead.
3. In a device of the character described, the combination with a side-bar bedstead and a bed bottom, of a bed bottom support-

ing device comprising a transverse element 30 having a single depending central portion, a flanged nut threaded on the lower end thereof, the flange having apertures therein spaced at intervals, and tension springs 35 engaged with flange apertures on each side of the depending portion and with the side bars of the bedstead.

4. In a device of the character described, the combination with a side-bar bedstead and a bed bottom, of a bed bottom supporting device comprising a transverse element having a depending central portion, means 40 for attaching the transverse element to the bed bottom, a flanged nut on the lower end of the depending portion, the flange having apertures therein spaced apart at regular intervals, a pair of tension springs having their 45 inner ends engaged in flange apertures on one side of the depending portion, and a pair of tension springs having their inner 50 ends engaged in flange apertures on the other side of the depending portion, plates each connected with the outer ends of the springs of a pair, and means for attaching the plates to the side bars of the bedstead. 55

In testimony whereof I affix my signature.

CLAYTON HOBERT.
